US00D510712S

(12) **United States Design Patent** (10) Patent No.: **US D510,712 S**
Chia et al. (45) Date of Patent: **** Oct. 18, 2005**

(54) **JEWELRY COMPONENT**

(76) Inventors: **Meang Chia**, 412 W. 6th St., Suite 1104, Los Angeles, CA (US) 90014; **Cheo Chia**, 412 W. 6th St., Suite 1104, Los Angeles, CA (US) 90014; **Huy Kim Chia**, 412 W. 6th St., Suite 1104, Los Angeles, CA (US) 90014

(**) Term: **14 Years**

(21) Appl. No.: **29/189,955**

(22) Filed: **Sep. 11, 2003**

Related U.S. Application Data

(62) Division of application No. 29/129,456, filed on Sep. 15, 2000, now Pat. No. Des. 482,295, which is a continuation-in-part of application No. 29/110,327, filed on Sep. 3, 1999, now Pat. No. Des. 471,129, which is a continuation-in-part of application No. 29/098,058, filed on Dec. 21, 1998, now Pat. No. Des. 418,445, which is a division of application No. 29/070,204, filed on May 7, 1997, now Pat. No. Des. 406,247.

(57) **CLAIM**

The ornamental design for a jewelry component, as shown and described.

DESCRIPTION

Reference is made to Applicants' Application No. 09/224, 936 filed Dec. 31, 1998 entitled "Decorative Jewelry

Article"; Application No. 09/383,814 filed Aug. 26, 1999 entitled "Decorative Jewelry Item"; U.S. Design Application No. 29,116,859 filed Jan. 11, 2000, entitled "Jewelry Component"; and U.S. Document Disclosure Certificate No. 459913, recorded Jul. 30, 1999.

FIG. 1 is a perspective view of a first embodiment of a jewelry component showing our new design;

FIG. 2 is a top plan view of the first embodiment;

FIG. 3 is a front elevational view of the first, second, third, fourth, and fifth embodiments, the rear, left, and right elevational views being identical images;

FIG. 4 is a perspective view of a second embodiment of a jewelry component showing our new design;

FIG. 5 is a top plan view of the second embodiment;

FIG. 6 is a perspective view of a third embodiment of a jewelry component showing our new design;

FIG. 7 is a top plan view of the third embodiment;

FIG. 8 is a perspective view of a fourth embodiment of a jewelry component showing our new design;

FIG. 9 is a top plan view of the fourth embodiment;

FIG. 10 is a perspective view of a fifth embodiment of a jewelry component showing our new design;

FIG. 11 is a top plan view of the fifth embodiment;

FIG. 12 is a perspective view of a sixth embodiment of a jewelry component showing our new design;

FIG. 13 is a top plan view of the sixth embodiment;

FIG. 14 is an enlarged partial cross sectional view taken along the line 14—14 in FIG. 13 to show only the feature of the sloping top;

FIG. 15 is a front elevational view of the sixth, seventh, eighth, ninth, tenth, and eleventh embodiments, the rear, left, and right elevational views being identical images;

FIG. 16 is a perspective view of a seventh embodiment of a jewelry component showing our new design;

FIG. 17 is a top plan view of the seventh embodiment;

FIG. 18 is an enlarged partial cross sectional view taken along the line 18—18 in FIGS. 17, 20, 22, and 24 to show only the feature of the sloping top;

FIG. 19 is a perspective view of an eighth embodiment of a jewelry component showing our new design;

FIG. 20 is a top plan view of the eighth embodiment;

FIG. 21 is a perspective view of a ninth embodiment of a jewelry component showing our new design;

FIG. 22 is a top plan view of the ninth embodiment;

FIG. 23 is a perspective view of a tenth embodiment of a jewelry component showing our new design; and,

FIG. 24 is a top plan view of the tenth embodiment.

It being understood that the broken lines are for illustrative purposes only and form no part of the claimed design.
